CLAIM

The ornamental design for an abutment for partition walls, as shown and described.

DESCRIPTION

FIG. 1 is a front elevation view of an abutment for partition walls;

FIG. 2 is a top plan view, the bottom being identical;

FIG. 3 is a rear elevation view thereof;

FIG. 4 is a left side elevation view thereof;

FIG. 5 is a right side elevation view thereof;

FIG. 6 is a perspective view thereof;

FIG. 7 is a front elevation view of a second embodiment of an abutment for partition walls;

FIG. 8 is a top plan view, the bottom being identical;

FIG. 9 is a rear elevation view thereof;

FIG. 10 is a left side elevation view thereof;

FIG. 11 is a right side elevation view thereof;

FIG. 12 is a perspective view thereof; and,

FIG. 13 is a perspective view thereof showing elements in broken lines for illustrative purposes only that do not form part of the claimed design.

The ornamental design of an abutment for partition walls pertain to elongated plaster moldings designed to run between a ceiling and a floor and having an abutment surface for abutment against the end surface of a partition wall or as a join between two such walls.

UNITED STATES PATENT AND TRADEMARK OFFICE
CERTIFICATE OF CORRECTION

PATENT NO. : Des. 622,415 S
APPLICATION NO. : 29/335688
DATED : August 24, 2010
INVENTOR(S) : Tony Baccarini

Page 1 of 1

It is certified that error appears in the above-identified patent and that said Letters Patent is hereby corrected as shown below:

On the Title page, Item (73), in "Assignees", lines 1-2, delete "Tony Baccarini, Bures Suffolk (GB); Nigel Aulton, Bures Suffolk (GB)" and insert -- Tony Baccarini and Nigel Aulton, Trading as Seamless Abutment Solutions, Bures Suffolk (GB) --, therefor.

On the Title page, Item (36), under "Foreign Application Priority Data", line 2, delete "Oct. 4, 2006" and insert -- Apr. 10, 2006 --, therefor.

Signed and Sealed this

Thirtieth Day of November, 2010

David J. Kappos
Director of the United States Patent and Trademark Office
